UNITED STATES PATENT OFFICE.

JAMES K. SHELTON, OF CUBA, ALABAMA.

WASHING-MACHINE.

1,159,281.

Specification of Letters Patent.

Patented Nov. 2, 1915.

Application filed June 17, 1915. Serial No. 34,727.

To all whom it may concern:

Be it known that I, JAMES K. SHELTON, a citizen of the United States, residing at Cuba, in the county of Sumter and State of Alabama, have invented certain new and useful Improvements in Washing-Machines; and I do declare the following to be a full, clear, and exact description of the invention, such as will enable others skilled in the art 10 to which it appertains to make and use the same.

My invention relates to useful improvements in washing machines and has for its object to improve upon the general construction of devices of this class to such an extent 15 as to not only provide an extremely efficient machine, but one which may be easily and inexpensively manufactured and marketed.

With this general object in view, the invention resides in certain novel features of construction and in unique combinations of parts to be hereinafter claimed and fully described by reference to the accompanying drawings wherein:

25 Figure 1 is a vertical section of a washing machine constructed in accordance with my invention; Fig. 2 is a horizontal sectional view as seen along the plane indicated by the line 2—2 of Fig. 1; and Fig. 3 is a bottom plan view of the washing head. Fig. 4 is a side elevation of the complete machine; and Fig. 5 is a top plan view thereof.

In this drawing, which constitutes a part of the application and in which like reference characters designate corresponding parts throughout the several views, the numeral 1 indicates a tub of any preferred formation having a removable top 2 whose central portion is constituted by a removable 30 door 3 which is normally closed by a pair of pivoted buttons 4.

Depending from the edge portion of the cover 2 is a plurality of upright slats 5 which are removable with said cover, the 45 lower ends of said slats being secured to the opposite ends of the crossed horizontally disposed slats 6 which are shown in the present application as resting upon the bottom of the tub. These slats co-act with the washing head previously described in a manner 50 yet to be set forth.

Having its intermediate portion revolvably mounted in an appropriate bearing 7 carried by the door 3, is an upright shaft 8 whose 55 downward movement is limited by a stop collar 9 resting on the aforesaid bearing,

said shaft, however, being allowed an appropriate amount of upward movement. The upper end of the shaft 8 is provided with a lever 10 whereby it may be oscillated 60 one third of a revolution, more or less, while the lower end of said shaft carried the washing head designated in the drawing by the numeral 11, such head being provided with a plurality of loops 12 to which the articles 65 to be washed are secured, whereby when the shaft is oscillated, such articles will be dashed against the upright slats 5 and will be drawn over the horizontal slats 6.

The head 11 includes a polyedged horizontally disposed board 13 here shown in the form of a diamond. Depending from the lower flat face of this board, at the edge portions thereof, is a plurality of upright flanges 14 having their ends beveled and disposed in contact at the several angles of the board. Nails or the like may be driven through the board 13 and flanges 14, if desired, but in most cases this is unnecessary due to the construction of the loops 12 above 80 mentioned.

The loops in question are in the form of upright C-shaped clips having their upper and lower ends flattened and extended in width to provide attaching plate 15, the several clips being heavily galvanized or tinned. These clips embrace the flanges 14 and the edge portions of the board 13, one clip being disposed adjacent each angle of the head. With the parts in these positions, the lowermost of the plates 15 contact with the adjacent ends of the several flanges 14 and driven fasteners 16 are passed through said plates and into said ends, while additional driven fasteners 17 are driven through the uppermost of the plates 15, the edge portions of the board 13 and into the flanges 14. It will thus be evident the same fasteners which secure the loops or clips 12 of the head, secure the several parts of the latter 90 together, this being extremely simple yet 95 highly efficient in construction.

In operation, the clothes to be washed are tied or otherwise secured to the several loops 12, the tub 1 is filled to the necessary extent with any appropriate washing fluid, and the lever 10 is so actuated as to oscillate the head 11, the result being that the clothes are 105 oscillated by the head and dashed against the slats 5 and 6, whereby such clothes are 110 effectively washed. During such operation of the machine, the diamond shaped box-like

head 11 imparts an agitating motion to the fluid in the tub, since the several angularly disposed flanges 14 serve as fluid deflecting means for throwing the water outward and 5 then allowing the same to again rush inwardly, this operation assisting materially in the proper action of the machine.

The tub 1 may be furnished as a part of the machine, in which case it will be provided with cleats 1^a for the attachment of a wringer, or the remaining parts of the invention may be manufactured and sold independently of the tub, it being evident that such parts may be made of various sizes and 15 may be applied to use upon ordinary wash tubs.

From the foregoing description, taken in connection with the accompanying drawings, it will be evident that although very 20 simple construction has been provided for carrying out the object of the invention, the latter will be efficient in operation and will possess a number of advantageous characteristics.

25 In the drawing, certain specific details of construction have been shown for accomplishing probably the best results, and in the preceding such details have been described, but it will be evident that I need not be limited thereto otherwise than to the extent to which the appended claims restrict me.

I claim:

30 1. A washing machine including an upright rotatably mounted shaft having oper-

ating means on its upper end, a horizontally disposed polyedged board carried by the lower end of the shaft, upright flanges extending vertically in one direction from one flat horizontal face of the board at the edge 40 portion thereof and having their free ends disposed contiguous to each other at the angles of the board, upright C-shaped clips embracing the edge portions of the board at the angles thereof and the ends of the 45 flanges at such angles, the intermediate portions of such clips being spaced outwardly from said flanges, fasteners passing through one end of the clips into the board, and additional fasteners driven through the other 50 ends of said clips into the adjacent ends of the several flanges.

2. A washing machine having an upright shaft, means for turning said shaft, and a diamond-shaped washing head carried by 55 the lower end of the shaft and comprising a horizontal plate member of diamond shape in top view, upright flanges depending from the four edges of the plate member and contacting at their ends beneath the corners of 60 said member and clothes attaching loops carried by the head adjacent the corners thereof.

In testimony whereof I have hereunto set my hand in presence of two subscribing witnesses.

JAMES K. SHELTON.
